Carl W. Sundberg, Birmingham, Mich., assignor
to Connecticut Telephone and Electric Corpora-
tion, Meriden, Conn., a corporation of Dela-
ware

Application November 30, 1950, Serial No. 13,199

Term of patent 14 years

(Cl. D26—14)

To all whom it may concern:

Be it known that I, Carl W. Sundberg, a citizen of the United States of America, residing in the city of Birmingham, county of Oakland, State of Michigan, have invented a new, original, and ornamental Design for a Telephone Base, of which the following is a specification, reference being had to the accompanying drawings, forming a part thereof, wherein:

Fig. 1 is a top plan view of a telephone base, showing my new design;

Fig. 2 is a side elevational view thereof;

Fig. 3 is an end elevational view;

Fig. 4 is a side elevational view taken from the opposite side of the device as viewed in Fig. 2; and

Fig. 5 is an end elevational view taken from the opposite end of the telephone base from that shown in Fig. 3.

The dominant features of my design are shown in full lines in the drawing.

I claim:

The ornamental design for a telephone base, substantially as shown and described.

CARL W. SUNDBERG.
